UNITED STATES PATENT OFFICE.

MAJC POTKALICKI, OF LILLY, PENNSYLVANIA.

SLED.

1,407,888.

Specification of Letters Patent. Patented Feb. 28, 1922.

Application filed March 17, 1920. Serial No. 366,529.

To all whom it may concern:

Be it known that I, MAJC POTKALICKI, citizen of Poland, residing at Lilly, in the county of Cambria and State of Pennsylvania, have invented certain new and useful Improvements in Sleds, of which the following is a specification.

This invention relates to sleds such as are used mostly by children for coasting on hills or inclines generally.

The invention has for an object to provide a simple and inexpensive attachment adapted for use to prevent sidewise slipping or skidding of the sled.

For further comprehension of the invention, and of the objects and advantages thereof, reference will be had to the following description and accompanying drawings, and to the appended claims in which the various novel features of the invention are more particularly set forth.

Fig. 1 of the drawings is a detail transverse sectional view through one of the runners of a sled equipped with the invention, this view being taken on the line 1—1 of Fig. 3.

Fig. 2 is a similar view but taken on the line 2—2 of Fig. 3.

Fig. 3 is a side view of the sled.

Fig. 4 is a transverse section on the line 4—4 of Fig. 3.

Fig. 5 is a detail vertical section on the line 5—5 of Fig. 1.

As here shown my improved sled comprises a pair of runners 10 having their front ends upturned in an ordinary manner as at 11, these runners being preferably of angular cross section with the vertical flanges on the inside thereof. These runners have secured to the upturned front ends thereof the front ends of a pair of longitudinal angle irons 12 whose rear ends are supported by a pair of legs 13 these legs preferably consisting of metal straps which are riveted at their ends as at 14 to the runners 10, the opposed halves of each strap inclining upwardly toward one another to unite in eyes 15. In these eyes are fixed, as by pins 16, the ends of a transverse rod 17 which passes through suitable apertures in the angle irons 12. These angle irons have riveted thereto as at 18 the top 19 of the sled.

To provide for mounting my improved

the vertical flanges of the runners 10 are preferably heightened as at 20 near the front and rear ends of the sled, these being preferably a front pair and a rear pair of these devices. The rear devices comprise a pair 60 of star-wheels 21 which are fixed on the inner ends of spindles such as 22 which extend freely through sleeves 23 slidable in curved slots 24 in the extensions, the sleeves each having a lip 25 which engages the wall of the 65 slot 24, to prevent displacement, while a projection 26 is formed on the lower side of each sleeve to provide a handle for adjustment. The main length of each of these slots 24 extends substantially vertically, with 70 preferably a slight forward inclination from the bottom to the top, while the ends of these slots turn backwardly in the form of offset recesses 27 and 28 in which the sleeves are adapted to be received.

The front devices are of the same general construction as the rear devices just described, being provided however with different adjusting means. Each of these devices comprises a star-wheel 30 similar to 80 the star-wheel 21 and fixed on the end of a short spindle 31 which extends freely through a sleeve 32 slidable in a slot 33 in the extension 20, a flange 34 on the sleeve preventing displacement thereof from the 85 slot. Each of these forward slots 33 is similar to the rear slots 24 being provided at its ends with offset recesses 35 and 36 similar to the recesses 27 and 28. Each of the sleeves 32 has fixed thereto the lower end of a vertical rod 40 which extends downwardly through a slot 41 in the runner extension 20 and is provided with a rigid outturned handle 42 on its upper end. A coiled expansion spring 43 which surrounds the rod 90 and bears between the top of the extension 20 and the head 42 normally tends to lift the star-wheel 30 upward, a washer 44 being preferably interposed between the spring and the top of the extension 20.

In the use of the device the spindles 22 and 31 of the star-wheels 21 and 30 may be adjusted from end to end of the slots 24 and the sleeves 23 and 32 engaged in either the upper offsets 27 or the lower offsets 28. In 105 the latter position the points of the star-wheels project below the runners 10 and engage the surface over which the sled is moving. When the sleeves engage in the upper offsets from the slots 24 the star-wheels are 110

raised completely above the said surface, as indicated in dotted lines in Fig. 3. As will be apparent, by reason of the backturned, or respective upward and downward disposition of the offsets 27 and 28 shoulders are interposed between the offsets and the main lengths of the slots which prevent the sleeves from moving laterally out of said offsets thus maintaining the star-wheels in the 10 raised or lowered position to which they may be adjusted.

Having thus described my invention what I claim as new and desire to protect by Letters Patent of the United States is as follows:

- 15 1. In a sled, an adjustable device adapted to engage the surface over which the sled travels for control purposes, an element on which said device is mounted, said element 20 passing through an upwardly extending slot in the sled runner, said slot having recessed offsets at each end thereof adapted to engage said element to retain said device in operative or inoperative positions.
- 20 2. In a sled, in combination with the runners thereof, upward extensions on said runners toward the front and rear ends thereof, said extensions having slots extending upward therein, said slots having offsets at 30 opposite ends turned backwardly beside the main lengths of the slots, elements slideable in said slots, and star-wheels mounted on said elements, said star-wheels being adapted to be localized in raised or lowered posi-

tions by engagement of the said elements 35 with the said offsets.

3. In a sled, in combination with the runners thereof, upward extensions on said runners toward the front and rear ends thereof, said extensions having slots extending upward 40 therein, said slots having turned backwardly beside the main lengths of the slots offsets at opposite ends, sleeves slideable in said slots, spindles rotatably carried by said sleeves, and star-wheels fixed on said 45 spindles, said star-wheels being adapted to be localized in raised or lowered positions by engagement of the said sleeves with the said offsets.

4. In a sled, in combination with the runners thereof, an upward extension on each of said runners adjacent the forward end thereof, said extensions having slots extending upward therein, said slots having backturned offsets at opposite ends turned backwardly 55 beside the main lengths of the slots, sleeves slideable in said slots, spindles rotatable in said sleeves, star-wheels fixed on said spindles, rods fixed on said sleeves extending upwardly in said extensions and 60 adapted to have longitudinal and vertical movement therein, handles on said rods, and springs surrounding said rods and normally urging the said star-wheels upwardly.

In testimony whereof I have affixed my 65 signature.

MAJC POTKALICKI.
